UNITED STATES PATENT OFFICE.

WILLIAM H. WHEELER, OF BELOIT, WISCONSIN.

WINDMILL.

SPECIFICATION forming part of Letters Patent No. 335,864, dated February 9, 1886.

Application filed April 3, 1885. Serial No. 161,156. (No model.)

To all whom it may concern:

Be it known that I, WILLIAM H. WHEELER, of Beloit, in the county of Rock and State of Wisconsin, have invented certain new and useful Improvements in Windmills, of which 5 the following is a description, reference being had to the accompanying drawings, which are made a part of this specification.

My invention is designed especially as an 10 improvement in geared mills, since it is in geared mills that the greatest difficulty is experienced in attaining those results which are accomplished by my improvements; but I do not desire or intend to limit myself to 15 geared mills, as my invention is equally applicable to other mills.

In all successful solid-wheel windmills it is necessary to have some means, first, whereby 20 the wheel may automatically regulate itself to the variations of the wind, and, second, whereby the wheel may be thrown either wholly or partly out of the wind by an operator acting from below the mill-head support or turn-table. In mills constructed prior to my invention the means for accomplishing both 25 these results have been located upon the mill-head above the turn-table, and devices for throwing the wheel out of wind have been brought under control of the operator by a rope or chain which passes from such devices 30 down past or through the turn-table and other supports of the mill-head. This connecting rope or chain will, it is found, as the mill-head is revolved by the changing direction of the 35 wind in many cases, and especially in geared mills, become tangled with the turn-table or shaft or other parts of the mill, and the above-mentioned devices will become inoperative.

It is the object of my invention to provide 40 means for overcoming these difficulties, and for performing other new and useful functions connected therewith.

To this end the principle of my invention consists, primarily, in fastening the wind-wheel frame or support to one and the tail-vane support to the other of two concentric tubes which are free to revolve the one within 45 the other, or relative to each other, the lower ends of said tubes being extended below the 50 supports upon which the mill-head rests, and in appropriately connecting with these tubes, at points below such supports, devices, first,

which act to automatically prevent the revolution of said tubes relative to each other, thus holding the wheel-face to the wind, and 55 against the force of the wind to turn it out, and proportionate to such force, and, second, by which the tubes may be revolved relative to each other, thereby turning the wheel out of wind; secondly, in the means whereby the 60 rotary motion of the wind-wheel may be transmitted to a vertical shaft which revolves freely within the inner of the two tubes above mentioned; and, thirdly, in the various sub-combinations, by which the performance of 65 the main features of the invention may be aided.

In the drawings, Figure 1 is an elevation of a windmill provided with my improvements in their preferable form. Fig. 2 is a vertical 70 section of the same. Fig. 3 is an elevation showing an alternate form of my improvements. Fig. 4 is a vertical section of the same. Fig. 5 is a detailed view of the devices, 75 preferably located at the foot of the tower, whereby the wind-wheel is held to the wind or thrown out of wind at will. Fig. 6 is an elevation of another form of my improvement. Fig. 7 is a vertical section of the same. Fig. 8 is a side view, and Fig. 9 a top view, of the 80 forked lever and arms therein shown, and hereinafter fully described. Fig. 10 is a horizontal section on the line *x* in Fig. 3. Fig. 11 is a horizontal section on the line *y* in Fig. 3. Fig. 12 is a detached view of the beveled gear and 85 gear-segments herein described. Fig. 13 is a detached view of the collar connected therewith. Fig. 14 is a vertical section, and Fig. 15 a top view, of the devices for centering the 90 vertical shaft. Fig. 16 is an elevation of the windmill-tower, near the base thereof.

Like letters represent similar parts in the several figures.

A, A, &c., represent the upright posts or supports of the windmill-tower.

B represents the mill-head or wheel-support, and C the shaft of the wind-wheel.

D represents the frame which supports the tail-vane of the windmill.

a represents a seat on the top of the tower, 100 in which the mill-head is mounted.

E represents the vertical shaft of the windmill.

Upon the inner end of the wind-wheel shaft

C is mounted the beveled gear c , which meshes with the beveled gear b^2 . The gear b^2 is mounted upon a short shaft, b' , which revolves in bearings b on the upper part of the mill-head 5 casting B. The lower end of the shaft b' is provided with an angular recess, which receives the upper end of the shaft E, which is finished to fit therein. By this means the revolution of the shaft b' , communicated there- 10 to from the wind-wheel shaft through the instrumentality of the gears c and b^2 , is transmitted to the vertical shaft E. The shaft b' could be omitted and the gear b^2 fixed directly to the shaft E below the gear c . This last 15 described construction, I am aware, is not new, and I consider it an inferior construction to that first described, because the tendency of the gears so arranged is to draw the wheel out of the wind, while in the construction first 20 described, (and which I consider new,) and with a wheel having its sails set in the usual way, there is no such tendency; but, on the contrary, whatever force the gearing may have acts to hold the wheel to the wind, and this is 25 the main object of such construction. I mention the second form because the other parts of my invention may be used as well with one form as the other, and I do not wish to be limited in the use of such other improvements 30 to any one particular form of connection between the wind-wheel shaft and the vertical shaft of the windmill.

Loosely surrounding the vertical shaft E is the tube G, and loosely surrounding the tube 35 G is the tube F, each tube being free to revolve independent of the other and of the shaft E.

In the preferable construction, as shown in Figs. 1 and 2, the frame D, which supports 40 the tail-vane, is rigidly attached to the outer tube, F, and rests upon its lower side upon the seat a, while its upper side is pivoted to the mill-head B, which rests in turn upon the frame D, and is rigidly attached to the tube 45 G. To the lower end preferably of the outer tube, F, is rigidly fastened the beveled gear e, as shown. To the lower end of the inner tube, G, are pivoted the beveled gear-segments 50 H H', which segments mesh with the gear e. Rigidly fixed to these segments are arms h h' , which are preferably bent, as shown in Fig. 55 12, so that their outer ends shall be in a line of a diameter of the shaft parallel to the plane of the segments. A collar, J, is loosely fitted upon the shaft E below the gear-segments H H', which collar is provided with a spherical upper end, j , and also with a strap, j' , upon one side. A socket, k, having the ears k k' , partially surrounds the ball end of the collar, 60 thus forming a ball-and-socket joint with the collar J. The rods K K' connect the ears k k' to the arms h h' of the gear-segments H H'. The shaft E revolves freely within the collar J, so that said collar may be retained in a 65 fixed position relative to the tower, while the ball-and-socket joint enables the gear-segments to assume any position relative to said

tower. A lever, L, passes through said strap j' , and is pivoted to some appropriate part, l, of the tower. The other end of the lever is attached to the rod M, which extends downward, and is connected with appropriate mechanism, hereinafter described, within reach of the operator.

A movement upward of the collar J causes, 75 through the instrumentality of the mechanism above described, a revolution of the gear-segments H H', which causes a revolution of the gear e. This produces a revolution of the tubes F and G relative to each other and in a contrary 80 direction, thereby causing a like revolution of the wheel-support B and tail-vane support D; but as the vane always remains in the line of the wind it is in practical operation, the tube to which the wheel-support B is attached, 85 which revolves, thereby carrying the wheel out of wind to any desired extent.

The construction above described may be varied to a considerable extent while retaining the same general principle of operation, 90 and accomplishing the same results. For instance, as shown in Figs. 3 and 4, the wheel-support may be attached to the outer tube, F. In that case the tube G projects to within the mill-head frame B, and is preferably sur- 95 mounted by a rigid cap, g. An arm, N, (shown most clearly in Fig. 11,) is rigidly attached to said cap g at one end, and is fastened to the ear d upon the vane-support D at the other end. When, now, the tubes are re- 100 volved relative to each other, the motion of the tube G is transmitted to vane-support D by said arm N, and thus the wheel-support and vane-support are caused to assume such relative positions as to throw the wheel out of 105 the wind; or such a construction as is shown in Figs. 12, 13, 14, and 15 may be employed, 110 wherein the gear e and gear-segments H H' are dispensed with. To the lower ends of each of the tubes F and G are fastened the 115 rigid arms O O', respectively, said arms hav- 120 ing the pulleys o o' pivoted to their outer ends. A forked arm, P, is attached to the socket k, and each branch of said forked arm is pro- 125 vided with the slots p p', within which the pul- 130 leys or wheels o o' operate. When with this construction the collar J is moved upward, the wheels o o', moving in the slots p p', cause the arms O O' to be brought into nearly the same vertical plane, thereby revolving the 130 tubes F and G and throwing the wheel out of wind.

The mechanism hereinbefore mentioned for controlling movement of the collar J, and thereby the wheel and vane supports, is illus- 125 trated in detail in Fig. 5 and in combination in Fig. 15. A two-armed lever, R, is pivoted to a stationary part of the tower and to a plate, S, provided with perforations s. To the upper arm, r, of the lever R the rod M is attached, while to the lower arm, r', a weight, W, is applied. This weight hangs nearly perpendicular when the wheel is full face to the wind, but moves in the arc of a circle toward 130

a horizontal position as the wheel is swung out of the wind, and thus forms a weight of varying resistance to control the position of the wheel, and enables the wheel to regulate 5 itself in a varying wind. When it is desired to throw the wheel out of wind, the operator pushes upward upon the arm r' . This movement is communicated by the rod M to the lever L , which moves the collar J , thereby 10 throwing, as before explained, the wheel out of wind. A pin, s' , in one of the perforations s in the plate S , beneath one of the arms of the lever R , retains the parts in any desired position.

15 I am aware of the patents granted to Sholes and Kelly, October 27, 1874, and of the patents granted to J. S. Adams, August 2, 1881, and I do not desire to claim any invention therein shown; but

20 What I do claim as new, and desire to secure by Letters Patent, is—

1. In a windmill, the combination of the wheel-support and vane-support with a vertical shaft, and means for transmitting the rotary motion of the wind-wheel thereto, and two concentric tubes attached, respectively, to said wheel-support and vane-support, and surrounding said shaft, and means applied to said tubes below the mill-head supports for revolving 25 said tubes relative to each other, for the purpose specified.

2. In a windmill, the combination, with the wheel-support and tail-vane support, and two concentric tubes rigidly attached thereto, respectively, of a beveled gear rigidly attached 35 to one tube and gear-segments pivoted to the other tube, and means for revolving said gear-segments, for the purposes specified.

3. In a windmill, the combination of the wheel-support and vane-support with a vertical shaft, and means for transmitting the ro-

30 tary motion of the wind-wheel thereto, two concentric tubes attached, respectively, to said wheel-support and vane-support, a beveled gear attached to one tube and beveled gear-segments pivoted to the other tube, a loose collar surrounding said shaft, with a ball-and-socket joint on one end thereof, rods connecting said ball-and-socket joint with said segments, and means for imparting a vertical motion to said collar, for the purpose specified. 45

4. The combination of the wheel-support and vane-support and two concentric tubes attached, respectively, thereto, with a weight of varying resistance connected with said tubes below the mill-head supports, for the purpose specified. 55

5. In a windmill, the combination, with the wheel-support, tail-vane support, and two concentric tubes attached, respectively, thereto, of a beveled gear attached to one tube, beveled gear-segments pivoted to the other tube, a vertically-moving collar having a ball-and-socket joint on one end, rods connecting 60 said segments and said ball-and-socket joint, 65 a lever for imparting a vertical motion to said collar, a rod pivotally connected to said lever, and a two-armed lever having a weight applied to its lower arm, substantially as and for the purpose set forth. 70

6. In a windmill, the combination, with the wheel-support and vane-support, of two concentric tubes, one tube being rigidly attached to the wheel-support, and means for revolving said tubes relative to each other, and an arm 75 attached to the other tube and to the vane-support, substantially as and for the purpose set forth.
